DESIGN FOR A HANDBAG

Benjamin Kalisher, Poughkeepsie, N. Y., assignor to Wood-Flex Fashions Inc., New York, N. Y., a corporation of New York

Application March 30, 1943, Serial No. 109,862

Term of patent 7 years

To all whom it may concern:

Be it known that I, Benjamin Kalisher, a citizen of the United States and a resident of Poughkeepsie, county of Dutchess, and State of New York, have invented a new, original, and ornamental Design for a Handbag, of which the following is a specification, reference being had to the accompanying drawing, forming a part thereof, in which:

Fig. 1 is a perspective view of the handbag embodying the new design and showing the top, front and a side wall thereof, and

Fig. 2 is a perspective view thereof showing the rear, bottom and opposite side wall thereof.

I claim:

The ornamental design for a handbag, substantially as shown.

BENJAMIN KALISHER.
